(57) **CLAIM**

The ornamental design for portable electronic device, as shown and described.

DESCRIPTION

FIG. 1 is a front perspective view of a portable electronic device in accordance with our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The broken lines throughout the views form no part of the claimed design.

1 Claim, 7 Drawing Sheets(56)
